Patented July 4, 1922.

FIG. 1

FIG. 3

JULIAN C. CALLAIS,
by
James L. Hopkins,
ATTORNEY.

UNITED STATES PATENT OFFICE.

JULIAN C. CALLAIS, OF ST. LOUIS, MISSOURI.

AMUSEMENT DEVICE.

1,421,907.

Specification of Letters Patent. Patented July 4, 1922.

Application filed June 10, 1920. Serial No. 387,924.

To all whom it may concern:

Be it known that I, JULIAN C. CALLAIS, a citizen of the United States, residing at St. Louis and State of Missouri, have invented 5 certain new and useful Improvements in Amusement Devices, of which the following is a specification, reference being had therein to the accompanying drawing.

My invention relates to improvements in 10 amusement devices and has for its object to provide a merry-go-round having balanced pairs of seats and propelled by the hand or foot movements of the passengers.

In the drawings:

15 Fig. 1 is a top plan view of a device embodying my invention, parts being broken away.

Fig. 2 is a side elevation of a fragment of the same, portions being shown in section.

20 Fig. 3 is an end view of one of the seat-carrying members and its driving mechanism.

The supporting frame 4 carries the annular rack 5 (having the flat horizontal flange 25 6) and the concentric support 7, having the ball-bearings 8 and vertical pintle 9. Upon the support 7 the spider 10 is revolvably and removably seated (see Fig. 2) having sockets 11 to receive the seat-carrying beams 12, pins 30 13 serving to lock said beams 12 in place.

Each of the beams 12 is provided at its outer terminal with a saddle-seat 14 and a reciprocating arm 15 having the handle-bar 16 and foot-bar 17. The arm 15 carries the 35 pawl 18, said pawl 18 rotating the axle 20 and gear 21 through the ratchet 19, the gear 21 meshing with the gear 22 on the shaft 23 to revolve the same with its fixed pinion 24. The wheel 25 is loosely mounted on the shaft 40 23 and travels on the upper face of the flange 6.

The shaft 23 is mounted in hangers 26 so that each of the beams 12 has its own driving mechanism attached to it and removable

with it from the device by withdrawing the 45 pin 13 and extracting the beam 12 from the socket 11.

By the described construction any number of pairs of the beams 12 may be employed, the spider 10 having as many of the sockets 50 11 as may be desired. The driving mechanism may be employed on one beam only if preferred.

Having thus described my invention, what I claim as new and desire to have secured to 55 me by the grant of Letters Patent, is—

1. In an amusement device, a circular rack, having a horizontal flange; a bearing having a vertical pintle and concentrically mounted within said rack; a spider having 60 sockets and revolvably mounted on said pintle; seat-carrying beams detachably mounted in said spider; a reciprocating arm having a handle-bar and a foot-bar and mounted at the outer terminal of each beam; a shaft 65 mounted beneath each of said beams, having pinions at its ends, the outer pinion geared to said reciprocating arm, and the inner pinion engaging said rack.

2. In an amusement device, a circular rack 70 having a horizontal flange; a bearing having a vertical pintle and concentrically mounted within said rack; a spider having sockets and revolvably mounted on said pintle; seat-carrying beams detachably mounted in said 75 spider; a reciprocating arm having a handle-bar and a foot-bar and mounted at the outer terminal of each beam; a shaft mounted beneath each of said beams, having pinions at its ends, the outer pinion geared to said 80 reciprocating arm, and the inner pinion engaging said rack, and a wheel loosely mounted on said shaft and traveling on the upper face of said flange.

In testimony whereof I hereunto affix my 85 signature.

JULIAN C. CALLAIS.
